BRACELET STRUCTURE AND METHOD OF
MAKING THE SAME

Karl Fassnacht, Cranston, R. I., and Lester W. Ballou, Attleboro, Mass., assignors to D. E. Makepeace Co., Attleboro, Mass., a corporation of Massachusetts

Application May 20, 1939, Serial No. 274,722

5 Claims. (Cl. 63—7)

This invention relates to an improved bracelet structure and method of making the same wherein the bracelet comprises two or more longitudinally curved sections hingedly connected together to form an ornamental bracelet structure.

One object of the invention is the provision of a novel bracelet structure adapted to be readily constructed from stock material of a conventional character and wherein the parts are easily assembled to form the bracelet.

Another object of the invention is the provision of a bracelet section of arcuate form comprising telescoping channel shaped members so constructed and arranged as to be capable of being assembled readily in opposed interfitting relation, with the parts retained in assembled relation by frictional engagement of the upstanding side edge portions.

Another object of the invention is the provision of a bracelet section comprising interfitting members each having upstanding edge portions interfitting together, the edge portions of one of said members being serrated throughout to permit longitudinal flexing of the member without distortion whereby it may be inserted into the curved shape of the other member from substantially straight stock and the parts retained in assembled relation through engagement of the upstanding edges.

A further object of the invention is the provision of a novel method of forming bracelet sections of this character by so constructing the parts as to permit the insertion of a substantially straight channel shaped element into telescoping relation with a permanently curved channel shaped member without distortion of either of the members.

Other objects and advantages of the invention relate to various improved details of construction and novel arrangements of the parts as well as various improved steps and arrangements of steps in forming and assembling the same as will be more fully set forth in the detailed description to follow.

Referring to the drawing:

Fig. 1 is a plan view of one form of the completed bracelet, showing two hingedly connected sections with the free ends of the sections shown in separated relation.

Fig. 2 is a perspective view of one of the members employed in forming a section of the bracelet structure, which member may be so made as to be permanently shaped and curved into the form to be assumed by the bracelet section upon completion,

Fig. 3 is a perspective view of a portion of the other member adapted for assembly with the member shown in Fig. 2 for forming the completed bracelet section,

Fig. 4 is a perspective view showing the manner of assembling the members shown in Figs. 2 and 3 in forming a complete bracelet section,

Fig. 5 is an enlarged transverse sectional view taken substantially along the line 5—5 of Fig. 1,

Fig. 6 is an enlarged sectional view taken 10 through the section 3, substantially along the line 6—6 of Fig. 1, and showing the keeper element for receiving the catch,

Fig. 7 is an enlarged longitudinal sectional view taken through the hinge connection of the sections, and showing the members in their assembled relation, and,

Fig. 8 is an enlarged transverse sectional view of a slightly modified form of bracelet section,

In the embodiment of the invention illustrated in Figs. 1 to 7 of the drawing, 1 designates the completed bracelet which may be formed from two or more longitudinally curved sections and which in the present embodiment consists of two arcuate sections 2 and 3 which are hingedly connected together as indicated at 4 and provided with fastening means for detachably connecting the ends of the bracelet sections together.

The fastening means employed for connecting the ends of the bracelet sections together may be any suitable or desired form of hinge structures and detachable connecting means. As shown herein they are separate elements adapted to be fitted within ends of the sections after their formation and held in place within the section ends in any desired manner, as by means of solder. The particular means shown herein for connecting end portions of the sections 2 and 3 comprise plates 5 and 6, insertible within the free ends of the sections, the plate 5 having a spring catch 7 provided with a boss 8, and the plate 6 having an upstanding portion serving as a keeper and provided with a catch receiving opening 9 for receiving the catch 7 to hold the section ends detachably connected.

Each bracelet section is formed of separate members 10 and 12 which may each be first shaped into substantially its final form and the members then telescoped one into the other in making the section. The member 10 may be 50 formed by drawing, rolling or otherwise shaping a piece of metal stock to provide a base portion 13 having opposite sides 14 located in upstanding relation with a portion of the base, and each side being provided with an inturned flange 15 ex- 55

tending inwardly from the upstanding side and towards the opposite upstanding side. The in-turned flanges 15 are preferably each equally spaced from the base 13 so as to be located in 5 substantial opposition with each other throughout their extents. The member 10 may be of a substantially rigid construction throughout its extent, being substantially permanently curved throughout into the form desired to provide a 10 bracelet section of a character appropriate for fitting about a portion of the wrist of the wearer, and is preferably of sufficiently heavy and rigid material to retain its shape and resist changes in shape or distortion under the usual conditions 15 of use.

The member 12 may be formed from flat stock in any suitable or desired manner as by cutting, stamping or the like, to serrate the edges, form teeth 16 separated by recesses 17, and provide 20 surface ornamentation 18 when desired. The teeth 14 on opposite side edges are then bent over to provide opposed upstanding toothed edges on opposite sides of the body portion 19 of the member. The member 12 upon completion of the 25 above operation may be slightly curved longitudinally of its extent or may be in the form of a substantially straight plate longitudinally of its extent and is capable of longitudinal flexing to a substantial degree without distortion of its 30 parts by reason of the serrations formed in the upstanding edges. The member 12 may also be formed of somewhat lighter material than the member 10 to facilitate the insertion of the member 12 into the channel of the substantially rigid 35 member 10.

The recesses 17 formed in the upstanding side edges of the member 12 are preferably of sufficient depth to terminate at points upon or closely adjacent to the base 19, whereby the base portion 40 19 is rendered capable of longitudinal flexing to the degree required for its insertion into the permanently curved member 10 without effecting any substantial distortion of the base portion 19. The upstanding teeth 16 forming the upstanding 45 side edges of the member 12 are preferably of a height slightly less than the radial distance separating the base 13 from the in-turned flanges 15 of the member 10 whereby the parts may be manipulated to insert the member 12 within the 50 channel of the member 10 with the teeth 16 extending towards and terminating closely adjacent to the outer curved face of the base 13 without allowing any substantial movement of the members 10 and 12 towards and from each other radially of their longitudinal curvature when located 55 in assembled relation.

In forming bracelet sections from the members 10 and 12, the substantially permanently shaped material from which the members 10 are 60 obtained may be made initially or cut to the length desired for the completed section. A suitable length may then be provided of the member 12 corresponding with that of the member 10, and one end of the member 12 inserted within 65 the channel of the member 10 with the ornamental face 18 of the base 19 located outwardly radially of the curve of the member 10. The member 12 is then forced into the channel of the member 10 by pressure exerted upon the opposed 70 base areas 13 and 19 so as to position the member 12 beneath the in-turned flanges 15 with the ends of the members 10 and 12 corresponding substantially with each other, after the manner indicated in Fig. 4 of the drawing.

75 By reason of the relative rigidity of the member

10 and the serrations formed in the edges of the member 12, the member 12 adapts itself readily to the curve of the member 10 and is held in position therein by frictional engagement of the upstanding side edges of the members.

5 After forming bracelet sections as above described, the sections may be hingedly connected together by any suitable means, which in the present form are shown as comprising hinge elements 20, each having oppositely positioned plates 22 connected by a hinge 21. As shown, the hinge plates 22 are each inserted in one end of a bracelet section to which they may be permanently connected by a layer of solder, as indicated at 23.

15 In that form of the invention shown in Fig. 8 of the drawing, a member 26, corresponding substantially with the member 10 previously described, is formed with a transversely rounded base 27 and upstanding inwardly directed transversely curved sides 28. A member 30, corresponding with the member 12 previously described, is formed with a base 31 and transversely curved serrated sides 32. After formation 20 of the members 26 and 30 as above described, the member 30 is inserted in the channel of the member 26, after the manner described in connection with that form of the invention shown in Figs. 1 to 7 inclusive, and the bracelet sections 25 may be forced into telescoping relation with each other in a manner similar to that previously described. The completed bracelet sections thus formed having the cross sectional shape as shown in Fig. 3 or similar thereto may be connected together for forming bracelets by means of suitable 30 hinge connections and catch and keeper structures suitably shaped to fit within and be secured to the ends of the section after the manner more particularly shown in connection with the form illustrated in Figs. 1 to 7 of the drawing.

35 In forming the member 12 the recesses 17 of the serrated edges may be of any suitable or desired shape,—rectangular, triangular or with curved sides to form differently shaped teeth 16 depending upon the shape of teeth or the recesses 40 desired, it being necessary only that the recesses be sufficient in number and suitably spaced from each other to permit the desired degree of longitudinal flexibility and that the teeth be adapted for frictional engagement with contiguous surfaces of the member 10.

45 What we claim is:

1. A bracelet structure comprising, two or more hingedly connected longitudinally curved sections, each of which is made up of telescoping 50 members, one of said members having upstanding side edges provided with inwardly directed flanges, the other member being longitudinally slidable within the upstanding side walls of said first named member and having upstanding 55 lateral edge portions extending inwardly towards the body portion of said first member and provided with serrations extending inwardly from the edges thereof to a depth sufficient to permit longitudinal flexing of the member without distortion.

60 2. A bracelet section comprising a longitudinally curved member having oppositely positioned upstanding side walls extending substantially throughout its length and inwardly directed 65 flanges carried by said side walls, and a second member fitting within said first member and having upstanding serrated lateral edges oppositely directed relative to the side walls of said first member and engaging frictionally the inner 70

faces of the side walls of said first member to resist sliding movement of said members relative to each other and maintain said second member in substantial engagement with the inwardly directed flanges of said first member, the serrations formed in the upstanding lateral edges of said second member extending inwardly throughout a substantial portion of the upstanding lateral edges to permit longitudinal flexing of said second member without distortion.

3. A bracelet structure comprising two or more sections hingedly connected together and each comprising inner and outer longitudinally curved members of channel shaped cross section arranged in telescoping relation with the upstanding side edges of each member extending towards the other member, and the upstanding side edges of the outer member interfitting within the upstanding side edges of the inner member, the upstanding side edges of said outer member being provided with serrations of a number and depth sufficient to permit longitudinal flexing of the member without distortion and the upstanding side edges of said inner member being each provided with an inwardly directed flange engaging the side edges of the outer face of said outer member.

4. In a bracelet structure comprising two or more arcuate sections hingedly connected together and each section having inner and outer members, said inner member being permanently

curved longitudinally of its extent and having outwardly directed upstanding lateral edge portions provided with inturned flanges, said outer member having upstanding edge portions provided with serrations of a depth sufficient to permit flexing of the member whereby it may be telescoped within said longitudinally curved inner member with its upstanding serrated edges extending inwardly of the curve of said inner member and located within and in opposed relation with the upstanding lateral edges of said inner member without distortion of said outer member in assuming the longitudinal curvature of said inner member.

5. The method of making longitudinally curved bracelet sections which comprises, shaping metal stock to form a channel shaped member of substantially rigid construction having a longitudinally curved body portion and upstanding side edges provided with inturned flanges substantially uniformly spaced from the body portion, shaping metal stock to form a longitudinally flexible member having upstanding serrated edge portions, and inserting said longitudinally flexible member within the channel of said first named member by endwise movement of the members with the upstanding edge portion thereof extending towards the body portion of said first named member.
